UNITED STATES PATENT OFFICE

2,532,132

CARDHOLDER

Paul R. Vogel, Chicago, Ill.

Application October 10, 1946, Serial No. 702,469

3 Claims. (Cl. 40—124)

1

This invention relates to card holders, and more particularly to a device adapted to hold greeting cards or photographs in a manner suitable for display purposes. The invention is an improvement on the device shown in my prior U. S. Patent No. 1,769,610, dated July 1, 1930.

One object of the invention is to provide a card holder whereby cards of various sizes may be mounted for display purposes. The cards are easily and quickly mounted and demounted, and they are held to the holder in a secure and neat manner.

Another object is to provide a card holder whereby cards of the same or various sizes may be mounted on either or both sides of the holder. In particular, cards of the same size may be mounted back to back on opposite sides of the holder, that is, the cards may occupy exactly the same area on opposite sides of the holder. This feature makes it possible for a plurality of holders to be mounted in album form and permits utilization of all available mounting space.

Still another object of the invention is to provide a holder whereby the cards may be attached through overlapping flap action on any or all of the card edges. Accordingly, cards may be mounted so as to be held with equal firmness along all four edges, top, bottom, right and left, thereby providing ideal support.

Other objects and advantages of the invention will be apparent as the description proceeds, reference being had to the accompanying drawing wherein various forms of the invention are shown. It is to be understood that the description and drawing are illustrative only, and that the scope of the invention is defined in the appended claims.

In the drawing:

Fig. 1 is a plane view of a card holder embodying the invention, and showing cards mounted on the holder;

Fig. 2 is a sectional view on line 2—2 of Fig. 1;

Fig. 3 is a sectional view on line 3—3 of Fig. 1; and

Fig. 4 is a plane view of a portion of a card holder utilizing a modification of the invention.

Referring now to the drawing, the improved card holder consists generally of a sheet 6 of comparatively stiff material such as cardboard. Sheet 6 may be of any suitable size and generally is of such size as to be conveniently mounted as one page of an album.

Sheet 6 is provided with a plurality of separate slits 7 and 8. Each slit (as exemplified by slits 7 and 8) follows in general the outline of a modi-

2

fied W. Accordingly, each slit defines in sheet 6 a group of three flaps, 9, 10 and 11, which are bendable out of the plane of the sheet on either side of the sheet. As will be seen, flaps 9 and 11 extend or face in the same direction, while intermediate flap 10 faces in the opposite direction.

Slit 7 is arranged in a row with additional slits 13, 14, 15 and 16, the space between adjacent slits in the row being somewhat less than the length of any one of the defined flaps.

Similarly slit 8 is arranged in a row of like slits spaced somewhat apart from the first described row. It will be understood that the number of such rows will depend upon the desired size of sheet 6.

Another row of separate slits, exemplified by slit 18 is disposed intermediate the first two rows. The slits of the intermediate row may have the same configuration as the others, and they are preferably reversed in direction. That is, flaps 19 and 20 defined by slit 18, face in a direction opposite to flaps 9 and 11 defined by slit 7, while intermediate flap 21 faces in the direction opposite to corresponding intermediate flap 10. Furthermore, the row of slits including slit 18 is staggered with respect to its adjacent rows, that is, the lengths of the flaps in the intermediate row lie generally opposite the spaces between slits in the adjacent rows. This staggered arrangement, of course, insures that cards of all sizes may be accommodated by the holder, and also that the stiffness of sheet 6 is not unduly lessened.

On the left side of sheet 6 are shown separate slits 22, 23 and 24. These slits are oriented at right angles to the previously described slits, each slit thereby providing groups of three flaps similarly oriented. The right side of sheet 6 is provided with oppositely directed separate slits 26, 27 and 28. Preferably, alternate slits in each of these rows are staggered with respect to adjacent slits, thereby providing flaps to accommodate cards of various dimensions.

A card 30 is shown mounted in position on the visible face of sheet 6. Flaps 9 and 11 of slit 7 and the corresponding flaps of slit 8 have been bent outwardly, and the top edge of card 30 has been inserted beneath the flaps. The intermediate flap of slit 16 and its counterpart in the corresponding other row overlap and secure the bottom edge of the card. The outer two flaps of side slit 23 overlap and hold the left edge of card 30, while the outer two flaps of slit 27 hold the right card edge.

As will be seen, the arrangement of flaps on card 6 is such as to accommodate cards of any

size, within the limits, of course, of sheet 6. Since several cards may be mounted on a single sheet, substantial space economy is effected.

A second card 31 is shown in dotted lines as being mounted on the reverse face of sheet 6. It is apparent that flaps are available for so mounting a card of any size on the reverse face. In fact, it will be seen that a card of exactly the same size as card 30 could be mounted on the reverse face to occupy a space exactly co-extensive with that occupied by card 30. That type of mounting would be accomplished by bending a flap such as flap 9, out of the plane of sheet 6 on one side, and its companion flap 11 out of the plane of the sheet on the opposite side. This procedure could be followed with sufficient of the flap groups to provide flap action on all edges of the reverse card.

The modification shown in Fig. 4 embodies generally the same invention as shown in Figs. 1-3. The modification utilizes, as shown, a sheet 34 containing spaced rows of separate slits 35 and 36. Slit 35 is substantially W-shaped so as to provide outer flaps 37 and 38 extending in the same direction, and intermediate flap 39 extending in the opposite direction.

A third row of separate slits 41 is disposed intermediate the rows containing slits 35 and 36. Slits 41 are substantially V-shaped, and each slit 41 defines a flap 42 which faces in the same direction as flap 39. It will be noted that flaps 42 may be somewhat shorter in length and spaced closer together than flaps 39 whereby flaps 42 are in general always staggered with respect to flaps 39. This feature, of course, permits the accommodation of cards of all sizes.

Use of the card holder shown in Fig. 4 is self-explanatory. It will be seen that cards of various sizes likewise may be mounted on both sides of the sheet.

From the above description it is thought that the construction and advantages of this invention will be readily apparent to those skilled in the art. Various changes and modifications may be made without departing from the spirit 45 or losing the advantages of the invention.

Having thus described the invention, what I claim as new and desire to secure by Letters Patent is:

1. A card holder comprising a sheet of stiff material having a plurality of separate, generally W-shaped slits therein, said slits each defining three flaps which are bendable out of the plane of said material on either side of said material, two of said flaps facing in one direction and the other flap facing in the opposite direction to comprise a flap group, said groups of three flaps being arranged in rows with the flaps of one row being staggered with respect to corresponding flaps in adjacent rows whereby cards 10 of the same or various sizes may be held by said flaps on either and both sides of said material, said flaps overlapping opposite card edges.

2. The card holder of claim 1 including additional rows of similar flap groups arranged in said material in areas laterally adjacent to some of said rows of flap groups, said similar flap groups being oriented at right angles to the first flap groups and being staggered with respect to each other whereby to hold cards by overlapping 25 the opposite card edges not overlapped by flaps of said first flap groups.

3. The card holder of claim 1 wherein the corresponding flaps in adjacent rows are oriented in opposite directions.
